UNITED STATES PATENT OFFICE.

FREDERICK A. SWAN AND CHARLES B. BOSWORTH, OF BOSTON, MASS.

ELECTRIC CUT-OUT.

SPECIFICATION forming part of Letters Patent No. 274,151, dated March 20, 1883.

Application filed July 17, 1882. (No model.)

To all whom it may concern:

Be it known that we, FREDERICK A. SWAN and CHARLES B. BOSWORTH, of Boston, in the county of Suffolk and State of Massachusetts, have invented a certain new and useful 5 Electric Cut-Out and Resistance Substitute, of which the following is a specification.

Our invention relates to that class of electric cut-outs in which it is desirable to cut out 10 a certain portion or branch of wires and not to interfere with the main line, the object being to so arrange the cut-out device that the operating of the cut-out substitutes in the line a resistance equivalent to the amount of resistance existing in the portion cut out. We attain 15 these objects by the mechanism illustrated in the accompanying drawings, in which—

Figure 1 is a diagram illustrating our devices. Fig. 2 shows the same in part, the 20 movable part of the cut-out being represented in the position which it occupies when the light and its wires are cut out of circuit. Fig. 3 is a view showing a vertical section taken on line X X of Fig. 1, and a perspective view of a 25 part of the top of the cut-out board.

B represents an electric light of ordinary construction, supplied with circuit-wires B' B³, which connect with the binding-posts B² B⁴. The wires L and L² are the line-wires which 30 connect with the binding-posts L' L³, one of which, L', is connected by a spring-plate, S', to an insulated bed-plate, C, while the other post, L³, is connected by a spring-plate, S, to the insulated bed-plate C'. The bed-plates C and C' 35 are shaped as shown, and attached to a block, E, which slides in the bed-piece A. The block E is held in position by the hook-pawl H, which engages with the projection E' on the slide E. The spring F is at tension, one end 40 acting upon E' on the sliding block E, while the other is fixed to the bed-piece A, so that the tendency is to cause the block E to slide in the direction of the arrow R when released from the hook-pawl H. The motion of the 45 hook-pawl H is controlled by the electro-magnet M, acting through the armature H', the electro-magnet M being charged by the wire D (connected to the light-wire B³) and the wire D', contact-breaker D⁶, D⁵, D⁴, D³, and wire D², 50 (connected to the light-wire B'). When the contact-breaker is open, as shown in the drawings, Fig. 1, the current passes to the light and does not affect the magnet M; but if the

contact at D⁵ D⁶ is made the magnet M acts and withdraws the hook-pawl H, thus releasing the block E and allowing it to be thrown by the spring F, so as to occupy the position shown in Fig. 2.

When it is desirable to have the light and its wires B⁶ and B³ in circuit the cut-out device is in the position shown in Fig. 1, in which case the current passes from the line-wire L² through post L³, spring-plate S, bed-plate C', spring-plate S², post B⁴, and wire B' to light; then through wire B³, post B², spring-plate S³, bed-plate C, spring-plate S', and post L' to line-wire L.

We will now describe our substitute resistance device, which is shown in Fig. 3 and partly in Fig. 2.

When the light and its wires are cut out the slide E occupies the position shown in Figs. 2 and 3; the line spring-plates S and S' resting on the bed-plates C and C², respectively, the plate C being joined to the vertical plate T, Fig. 3, and the plate C² to the vertical plate T', so that a connection of the plates T and T', Fig. 3, will complete a circuit between the line-wires L and L². (See Fig. 2.) This connection is made as follows:

K and K', Fig. 3, are two brushes resting on the plates T T', as shown, the brushes K and K' being each provided with a metal bracket-piece, N N', the two brackets N and N' being connected by a piece, P, of comparatively great resistance, its actual resistance being equal to the resistance of the light-wires, the light itself, and the connecting parts, so that the cutting out of the light does not affect the total resistance on the line.

P' is a contact-closer, which may be used when it is not desirable to introduce additional resistance into the line.

We claim—

In an electric cut-out and resistance device, 95 the combination of the cut-out mechanism, consisting of the electro-magnet M, catch H, and switch-block E, with the brushes K K', and resistance-piece P, all operating together substantially as described, and for the purpose 100 set forth.

FREDERICK A. SWAN.
CHARLES B. BOSWORTH.
